Term of patent 14 years

Int. Cl. D7—02

U.S. Cl. D44—1

FIG. 1

FIG. 2

FIGURE 1 is a top plan view of a cookie baking sheet showing my new design.

FIGURE 2 is a cross section on line 2—2 of FIGURE 1.

The characteristic feature of the design resides in the parallel elongated slots in the central longitudinal areas.

This application is a continuation in part of my application Ser. No. D. 12,747 filed June 15, 1968, now Patent D. 214,280.

I claim:

The ornamental design for a cookie baking sheet, as shown and described.
